UNITED STATES PATENT OFFICE.

JOHN C. FYFE, OF DENVER, COLORADO.

INCLOSED SUPPLY SYSTEM FOR ELECTRIC RAILWAYS.

SPECIFICATION forming part of Letters Patent No. 472,447, dated April 5, 1892.

Application filed December 26, 1890. Serial No. 375,917. (No model.)

To all whom it may concern:

Be it known that I, JOHN C. FYFE, a citizen of the United States, residing at Denver, in the county of Arapahoe and State of Colorado, 5 have invented certain new and useful Improvements in Appliances for Electric Railways; and I do hereby declare the following to be a full, clear, and exact description of my invention, such as will enable others skilled 10 in the art to which it appertains to make and use the same.

My invention relates to electric railways; and the object thereof is to provide improved appliances by which current may be supplied 15 to any desired number of motors placed upon cars moving upon a suitable track by means of a series of distributing-points arranged at suitable distances apart along the line of the main conductor, and suitable connections, whereby current may be taken from the 20 main conductor at the several distributing-points through normally-open local circuits or branches from the main conductor, which circuits are automatically closed by the mechanical action of the moving car and opened 25 immediately after the car has passed the local circuit.

The invention is specially designed for use 30 in connection with the "multiple-arc" system of electric railroading; but the same method of electric distribution is adapted to be applied to other uses.

The principle object of my invention is to provide improved means for supplying current 35 to the motors on the moving cars without exposing the conductors or contacts.

Another object is to provide improved means for automatically making the connection between the main conductor and the conductor 40 which conveys current to the car-motors in such a manner as to make complete contact without burning, blistering, corroding, or wearing out the contact.

A further object is to insulate and protect 45 the contact-bar or plow from rain, water, &c., which drips down through the conduit and falls upon the contact-bar in the underground conduit, and, finally, to provide improved means for connecting and disconnecting the 50 feeder-wire and contacts with the main conductor.

With these several objects in view my in-

vention consists in the means and appliances substantially as hereinafter described, and particularly pointed out in the claims at the 55 end of this description.

In the accompanying drawings, forming a part of this description, Figure 1 represents a vertical sectional view of the "junction-chamber," showing the connection between 60 the end portions of the adjacent sections of the main wire or conductor and the feed-wire, with the end portions of the wires dipped in mercury. Fig. 2 is a sectional view taken through the "contact-chamber" and illustrating the connections therefrom to the main conductor and plow or skate suspended from the car within the slotted underground conduit; and Fig. 3 is a side view of the skate and insulating bar and cover suspended from 70 the car, the supporting-plates thereof being broken off.

The main conductor F may be located underground at one side of or between two or more tracks outside of the rail. The conductor is formed in sections of suitable lengths, which may have their meeting ends bent downward, as indicated in Fig. 1, and dipped or immersed in mercury. Instead of uniting these ends by the ordinary union-joint, I use the "junction-box" B, (shown in said figure,) which consists, preferably, of a round or other suitably-shaped box, preferably of cast-iron, of the desired size to admit the ends of the joints of pipe according to 80 the demands or size of the system. This box is lined with heavy asbestos insulation E E, and is made air and water tight by screwing on the cap A with suitable packing. Sections of pipe H H, corresponding in length 85 to the sections of conductor F F, have their ends screwed into the box B, and may be made water-tight by "leading" with red lead, thus hermetically sealing the junction-box. The wires F F are provided with suitable in-

95
sulating material G, which, together with said wires, is contained within the pipes H H. The ends of the wires F F within the junction-chamber extend downward into a suitable receptacle or crucible C, which contains mercury, into which said wires are dipped or immersed. Into the side of the box B, preferably at right angles to the pipes H, is screwed 100 a small pipe K, containing a small "feeder-

wire" I, which is also provided with suitable insulation J J, surrounding the same within the pipe. The end of the wire I is also bent downward into the mercury D in said crucible, and is preferably arranged with its end between the bent ends of the wires F F, as shown. The other end of the feeder-wire I extends outwardly the desired distance from the junction-box B, and its containing tube or pipe is screwed into the contact-chamber P, as shown in Fig. 2, the end of the wire passing into the box or chamber and being bent downwardly into the mercury O, contained in a receptacle or crucible N, placed in said chamber.

The connections thus far described are permanent, so that a current passing through the main conductor will pass thence to the feeder-wire I, and thence, by means of suitable connections, to the motor on the car.

The chamber P may consist of a cast-iron box of suitable size and shape, but preferably square, and which may be bolted to the frame or side of the conduit. Fitted into the chamber 25 P, through a suitable stuffing-box and gland, is a short tubular shaft or iron tube, which is adapted to rock upon a pivot, as at 1¹, Fig. 2, for a purpose to be described. This pivotal shaft or tube has suitably secured thereto 30 within the chamber P a pipe-section or tube L, which projects upwardly and above the crucible N. On the end of the tubular shaft, outside of the chamber P, is attached the hard wood or other suitable insulating trolley-supporting 35 arm R, which supports the metal contact or trolley wheel S. To the axle X of the contact-wheel is secured an insulated wire, which extends through the tubular supporting-arm R into and through the tubular shaft, as 40 shown in dotted lines in Fig. 2, and up through the pipe L, terminating in a bent end portion M, which is turned downwardly over the crucible N, so as to be readily dipped into the mercury therein. The wire M is held normally out of contact with the mercury by 45 means of a spring 3, which connects the chamber P with the projecting portion of the arm R, as shown in Fig. 2; but when the contact-wheel is engaged by the skate T, the free end 50 of the supporting-arm will be depressed, thereby, so as to dip the wire M into the mercury, as indicated in full lines in Fig. 2, and establish electrical connection between the main conductor and the connections leading 55 to the wiring of the motor on the car. A flat spring Y is attached to the end of the axle X and bears against the outside of the contact-wheel S, so as to insure electrical contact between the metal axle X, forming virtually a 60 continuation of the wire M and the metal wheel S. It will thus be seen that the metal contact-wheels are the only exposed parts between the "power-house" and the motors on the cars in my improved system, and these 65 parts are only exposed to the air during the period of electrical connection when contact is made with the mercury in crucible N by

depressing the wire M, the spring 3 serving to break the connection immediately after the skate escapes from the contact-wheel on 70 the passage of the car by raising the trolley-supporting arm and lifting the end of the wire M out of the mercury, as indicated in dotted lines in Fig. 2. The contact-wire over the mercury in the contact-chamber P 75 will ordinarily, when not in use, be suspended about two inches above the mercury, the spring 3 serving to maintain the arm in this position. To prevent any undue shock when the contact-wheel is released by the 80 contact bar or skate I provide a stop Q, which is cushioned at its lower end, and against which the supporting-arm strikes when released by the skate, the arm being drawn upward against the stop by the action 85 of the spring 3. Projecting downwardly from the car into the conduit are two thin steel plates W W, to which is secured by bolts Z Z an insulating-strip V of any suitable material, preferably hard wood, which extends 90 nearly the entire length of the skate-shaped contact-bar T, and provides insulation between the skate and the steel plates W W, and also serves as a roof to protect the contact bar or skate T from rain, water, or mud, 95 which drips down through the conduit-slot, said strip being of a width sufficient to project over the bar T at either side thereof far enough to protect the same from such drippings. The under side of the strip V is 100 grooved or concave, as shown in Fig. 2, for the purpose of maintaining a perfectly-dry surface adjacent to the bar T, thereby insuring perfect insulation against "grounds" 105 between the bar T and the steel plates in the conduit-slot. The contact-bar T is securely bolted to the strip V at each end and is provided with a copper bolt U at or about the center thereof, which connects with a flat strip of insulated copper wire U', which 110 extends upwardly between the bars W W and connects with the wiring of the motor on the car, so as to establish electrical connection with the motor when current is passing from the main conductor through the described 115 connections in the contact-chamber and the wire in the tubular supporting-arm of the metal contact-wheel to the skate.

It will, of course, be understood that when electrical connection is established between 120 the main conductor and the car-motor the current will pass as usual through the car-wiring to the trucks and through the wheels to the rails or other connections to the return conductor, and thence to the generator at the 125 power-house.

For the purpose of passing curves the contact-wheels will be made about twice as long as the wheels in the straight portion of the track, so as to accommodate the sweep of the 130 skate.

From the foregoing description the operation and advantages of my invention will be readily understood.

In a practical electric-railway system the distance between the contact-chambers and junction boxes or chambers may be varied to suit the requirements; but they are usually placed about twelve feet apart, and with such an arrangement the skate-shaped contact-bar is made about fourteen feet long, so that there will always be one or two of the contact-wheels on duty. When the car is moving, the contact-wheel through which the current is passing into the contact-bar is not released before the contact-bar makes contact with the wheel in advance, so that the current is always in contact with the skate depending from the car, whereby the motor-man may open and close the circuit at will by the usual operating appliances now in common use. In such a system, the current being supplied to a number of motors by the same positive wire and returned to the generator by the same negative wire or by the rails, the throwing out of contact of any of the motors will not affect the main current by breaking circuit in the contact-chamber, which lies in (as it were) only one branch of the many branches which go to form a circuit between positive and negative conductors in multiple arc, and if the current does not find a leak to the ground between the main conductor and the motor there is no ground, or, as it is commonly termed, "short circuit." The junction-box in the main conductor and the contact-chamber attached to the conduit being lined with heavy asbestos insulation, and the connecting-wires of the various parts being not only heavily insulated, but the insulation being also protected (in one case) by being inclosed in a pipe filled with insulating material and in the hard-wood supporting-arm, (which is a good non-conductor if kept painted,) and the contact-bar being insulated from the steel plates by the hard-wood "under-grooved" insulating-strip, and the copperstrip passing up from the contact-bar through heavy insulation, through the steel plates to the car-wiring, to the motor on the car, there is no possibility of a short circuit, and yet perfect electrical connection may be established between the motor on the car and the main supply-conductor, so as to supply current to the motor on the moving car. Over that portion of the track over which the car is passing there will of course always be the contact-wheel borne down and exposed; but such exposure is simply to the atmosphere, and but for a moment, when it is pulled up by the spring and released from duty, and the mechanical connection between the motor on the car and the main conductor is made automatic, and yet so as to insure complete contact without burning, blistering, corroding, or wearing out the contact, as in previous systems, owing to the use of mercury in making the connection, and by the same means electrical connection is established between the feeder-wire and the main conductor-sections,

and the circuit may be readily broken by simply lifting the ends of the wire out of the mercury. This construction also affords an easy means of connecting and disconnecting the 70 feeder-wire and the ends of the main conductor-sections, permitting them to be readily removed by simply lifting them out of the mercury in the junction-box.

Having thus described my invention, what I 75 claim as new, and desire to secure by Letters Patent, is—

1. In combination with the main conductor, the feeder-wires extending therefrom at intervals along the line of said conductor, normally-open local-circuit connections correspondingly arranged along the line of said conductor, adapted when closed to take current through mercury in contact with said feeder-wires, and mechanism actuated by a 85 moving car for making contact between said circuit connections and the mercury in contact with said feeder-wires, so as to automatically close the local circuits, substantially as described. 90

2. The combination, with the main conductor having distributing-points arranged at intervals along the line thereof, of contact-chambers containing mercury correspondingly arranged along the line of said conductor, feeders connecting said distributing-points with the mercury in said chambers, normally open local-circuit connections at said distributing-points adapted when closed to take current from the main conductor through 100 the mercury in said contact-chambers, and mechanism adapted to be actuated by a moving car, so as to automatically close said local circuits through the motor on the car by making contact with the mercury in said contact-chambers, substantially as described. 105

3. In an electric railway, the combination, with the main conductor having a series of distributing-points arranged along the line thereof, of junction-boxes containing mercury 110 at said distributing-points, normally-open local-circuit connections correspondingly arranged along the line of said conductor, including contact-chambers containing mercury in contact with conductors connecting with 115 the mercury in said junction-boxes, and mechanism actuated by the car for closing the local-circuit connections through the motor on the car by making contact between said circuit connections and the mercury in said contact-chambers, substantially as described. 120

4. A system of electric distribution comprising a main conductor having distributing-points arranged at suitable distances apart throughout its length, normally-open local-circuit connections, including mercury, correspondingly arranged along the line of said conductor, branch conductors or feeders leading from said distributing-points to the mercury of said connections, and means for making contact with the mercury, so as to close the local circuits, substantially as described. 130

5. In an electric railway, an electric conductor composed of insulated sections having their adjacent end portions secured in close proximity within a sealed box or junction-chamber containing mercury, into which the free ends of the conductor-sections are dipped or immersed so as to establish electric connection through the mercury, substantially as described.
- 10 6. In an electric railway, an electric conductor composed of insulated sections having their adjacent end portions detachably secured in close proximity within a sealed box or junction-chamber containing mercury, into which the free ends of the conductor-sections are dipped or immersed so as to establish electric connection through the mercury, substantially as described.
- 15 7. In combination with the main conductor composed of sections having their adjacent end portions dipped in mercury contained within a sealed vessel or junction-box, the feeder-wire extending from adjacent local-circuit connections into said box, and having its free end dipped in the mercury therein, substantially as and for the purpose set forth.
- 20 8. In combination with the main conductor composed of sections having their adjacent end portions dipped in mercury contained within a sealed vessel or junction-box, the removable feeder-wire connecting the mercury in said chamber with mercury contained in a second sealed chamber, of a normally-open local circuit, substantially as described.
- 25 9. In combination with the sectional conductor and the junction-chamber having the crucible of mercury therein, the contact-chamber provided with a similar mercury-containing crucible, the feeder-wire connecting the mercury in said crucibles, connections normally out of contact with the mercury in said contact-chamber for conveying current therefrom to the car-motor, and means for closing the electric circuit from the main conductor
- 30 45 through the mercury in said crucibles by making contact between said connections and the mercury in said contact-chamber, substantially as described.
- 35 10. In combination with the sectional conductor and the junction-chamber having the crucible of mercury therein, the contact-chamber provided with a similar mercury-containing crucible, the feeder-wire connecting the mercury in said crucibles, connections normally out of contact with the mercury in said contact-chamber for conveying current therefrom to the car-motor, and appliances for automatically closing the electric circuit through the mercury in said crucibles by the action of
- 40 60 the car, substantially as described.
- 45 11. The combination, with the main conductor having a series of distributing-points along the line thereof, of hermetically-sealed junction - boxes at said distributing-points, normally-open local circuits along the line of the railway connected with said distributing-points by feeder-wires leading from said junction-boxes to similarly-sealed contact-chambers, and mechanism, substantially as described, for closing the local circuits through the motor on the car by the mechanical action of the car, substantially as described.
- 50 12. In combination with the contact bar or skate and its supporting-plates, the insulating-bar concaved or grooved on the lower side thereof and supported above the skate out of contact therewith, so as to provide a dry surface adjacent to said skate and also form a roof or cover therefor, substantially as described.
- 55 13. In combination with the main sectional supply-conductor having the junction-chambers arranged at suitable distances apart along the line thereof, the contact-chambers similarly arranged along the line of the railway, feeder-wires connecting crucibles of mercury placed in said chambers and pivoted tubular arms inclosing wires having contact-points held normally out of contact with the mercury in the contact-chambers and projecting therefrom beneath the slot in the conduit in position to be actuated by the depending plow or skate carried by the car, so as to close the local circuits through the wire in the said arms by causing the same to make contact with the mercury in the contact-chambers.
- 60 14. In combination with the main conductor, the contact-chamber containing a crucible of mercury, the feeder-wire leading from the main conductor into the mercury in said crucible, the pivoted arm carrying the insulated wire, having its free end held normally out of contact with the mercury in the contact-chamber by yielding spring-pressure, and the contact-wheel supported on said pivoted arm beneath the slot in the conduit in a position to be depressed by the action of a depending skate or plow carried by the car, so as to make contact between the wire of the contact-supporting arm and the mercury in the contact-chamber.
- 65 15. In combination with the sealed contact-chamber, the pivoted contact-supporting arm, the insulated wire extending through the same to a position immediately above a crucible of mercury in said contact-chamber, and a spring adapted to hold the said arm in an elevated position with the wire thereof out of contact with the mercury in the contact-chamber.
- 70 16. In combination with the pivoted spring-actuated contact-supporting arm, the cushioned stop adapted to limit the upward movement of said arm, substantially as described.
- 75 17. In combination with the pivoted insulating supporting-arm carrying the insulated contact-wire, the contact-wheel, and the spring at the end of the supporting-arm adapted to convey current from the metallic connections or axis of said supporting-arm to the contact-plow through the metal contact-wheel, substantially as described.
- 80 18. In combination with the contact bar or

skate, the insulating-bar attached thereto, the
steel plates secured to said insulating-bar,
and the insulated wire inclosed between said
plates, having its lower end projecting be-
5 neath the insulating-bar and attached to the
skate, said insulating-bar being adapted to
provide insulation between said steel plates

and said contact bar or skate, substantially
as described.
